Fig. 3**Fig. 4***To all whom it may concern:*

Be it known that I, Frederick G. Knowles, a citizen of the United States of America, residing in Rochester, in the county of Monroe and State of New York, have invented a new, original, and ornamental Design for a Motion-Picture Projector Carrying Case, of which the following is a specification, reference being had to the accompanying drawings, forming a part thereof, in which:

Fig. 1 is a perspective view of a motion-picture projector carrying case taken from the front and showing my new design;

Fig. 2 is a view similar to Fig. 1 but taken from the opposite side of the motion-picture projector carrying case shown in Fig. 1;

Fig. 3 is a top plan view of the motion-picture projector carrying case shown in the preceding figures; and

Fig. 4 is an end elevation of the motion-picture projector carrying case shown in the preceding figures.

I claim:

The ornamental design for a motion-picture projector carrying case, as shown.
